W. I. SHERWOOD,
CARRIER FOR BOTTLES,
APPLICATION FILED NOV. 16, 1916.

1,236,610.

Patented Aug. 14, 1917.

UNITED STATES PATENT OFFICE.

WILLIAM I. SHERWOOD, OF UPPER MONTCLAIR, NEW JERSEY, ASSIGNOR TO CORDLEY AND HAYES, OF NEW YORK, N. Y., A CORPORATION OF NEW YORK.

CARRIER FOR BOTTLES.

1,236,610.

Specification of Letters Patent. Patented Aug. 14, 1917.

Application filed November 16, 1916. Serial No. 131,727.

To all whom it may concern:

Be it known that I, WILLIAM I. SHERWOOD, a citizen of the United States, residing at Upper Montclair, in the county of Essex, State of New Jersey, have invented certain new and useful Improvements in Carriers for Bottles, of which the following is a description, reference being had to the accompanying drawings, forming a part 10 hereof.

My invention relates to carriers for bottles, jars and other articles to be lifted or carried by hand and has for its object to provide a simple strong and inexpensive device 15 particularly adapted for lifting and carrying heavy bottles of water, demijohns and the like which will firmly grasp and hold the article to be carried and may be easily released from it and in which the 20 greater the weight to be carried the more firmly will the article be held.

With these and other objects hereinafter explained in view my invention consists in the construction and combination of elements 25 hereinafter described and claimed.

Referring to the drawings:

Figure 1 is a perspective view of a carrier embodying my invention in position on a bottle.

Fig. 2 is a central vertical sectional view of the carrier shown in Fig. 1.

Fig. 3 is a horizontal sectional view of the carrier on a plane below the points at which the carrier members are hinged together.

Fig. 4 is a partial side view of a carrier showing a modified form of hand grasp and

Fig. 5 is a view similar to Fig. 4 but showing a second modified form of hand grasp.

In the drawings 1 and 2 are two carrier 40 members each formed of stout wire to form a handle portion and two legs depending therefrom. The legs of carrier member 1 are each bent midway of its length to form a coil 3 and each is bent at its end to form

an eye 4. The carrier member 2 has its legs each bent midway of its length to form a pivot 7 parallel with the handle portion 10 adapted to extend through and turn in coil 3 of the carrier member 1, and each of its 45 legs is provided at its end with an eye 8.

The carrier members 1 and 2 are each provided at their lower ends with clamping members 5 each provided on each of its ends with an eye 6 for engagement with eyes 4 of

the legs of member 1 and eyes 8 of the legs 55 of member 2.

The handle portions 9 and 10 of the carrier members are so arranged that both may readily be grasped by the hand of the person using the device. The eyes 6 of the 60 clamping members 5 are formed by bending the ends of the clamping member upward and inward, and the eyes 4 and 8 of the carrier members are formed by bending the ends of the legs inward and upward. The 65 clamping members are thus free to swing slightly so as to adapt themselves to the neck of the bottle or other article on which the device is used.

The handle portions 9 and 10 may be left 70 free to be grasped by the hand of the user of the device and when so used the pressure of the hand will tend to force the handle portions toward each other and to thereby force the clamping members 5 toward each 75 other and thus make the grip on the article proportional to its weight, but I prefer to provide these handle portions with a hand grasp convenient for the hand which will have a cam action on the handle portions to 80 force them toward each other as the article to be carried is lifted.

The hand grasp shown in Figs. 1 and 2 consists of a piece of sheet metal 11 bent into an arc shape as shown with one edge 12 bent 85 to inclose the handle portion 9 and having its other edge 13 bent upward to form a stop for the handle portion 10. The edge 12 turns freely on the handle portion 9 and the body of the hand grasp extends under the 90 handle portion 10. When the clamping members 5 are to be placed about the article to be lifted the handle members may separate until the handle member 10 reaches and is stopped by the inturned end 13. When 95 the carrier is in position and the bottle or other article is to be lifted the grasp of the hand on the hand grasp causes it to swing on the handle member 9 and to act as a cam on the handle member 10 to force it toward 100 the handle member 9 with a pressure depending on the weight of the bottle or other article to be lifted and carried.

In the modified form shown in Fig. 4 the piece of sheet metal 14 corresponding to the 105 piece 11 of Figs. 1 and 2 is formed into a triangular shape in cross section inclosing both handle members 9 and 10. When the

clamping members 5 are to be separated to be placed over the neck of a bottle, the hand grasp rests on the handle members as shown in full lines. In lifting the article to be carried the hand grasp moves upward and its converging sides force the handle members together as indicated in dotted lines.

In the modification shown in Fig. 5 the sheet metal piece 15 forming the hand grasp is bent into elliptical form in cross-section. When the clamping members are in open position the hand grasp rests on the handle members 9 and 10 with its longer diameter horizontal. When the article is to be lifted the hand grasp is turned so that its shorter diameter is horizontal as shown in dotted lines forcing the handle members toward each other.

The clamping members 5 are shown bent to fit the neck of a bottle. They may of course be bent to any other form suitable to the article to be grasped and lifted.

Having thus described my invention what I claim is:—

1. A carrier for bottles and the like comprising two members pivotally connected midway of their length provided at one end with means for grasping the article to be carried and provided at their other ends with handle portions, and a hand grasp inclosing the handle members and so formed as to exert a cam action on the handle portions to force them toward each other.

2. A carrier for bottles and the like comprising two members pivotally connected midway of their length provided at one end with means for grasping the article to be carried and provided at their other ends with handle portions, and a hand grasp bent at one end about one of the handle portions and inclosing the other handle portion with-

in its body, its body being curved to form a cam for forcing the second handle portion toward the first.

3. A carrier for bottles or like containers comprising two carrier members each formed of a single piece of wire and each having a handle portion and legs depending therefrom, the legs of one carrier member being each bent midway of its length to form a coil, and having an eye at its end, the legs of the other carrier member being each bent midway of its length to form a pivot extending through and adapted to turn in one of said coils and having an eye at its lower end, and clamping members having an eye at each end engaging an eye of a leg of one of the carrier members and bent between its ends to conform to a bottle neck.

4. A carrier for bottles or like containers comprising two carrier members each formed of a single piece of wire and each having a handle portion and legs depending therefrom, the legs of one carrier member being each bent midway of its length to form a coil, and having an eye at its end, the legs of the other carrier member being each bent midway of its length to form a pivot extending through and adapted to turn in one of said coils and having an eye at its lower end, and clamping members having an eye at each end engaging an eye of a leg of one of the carrier members and bent between its ends to conform to a bottle neck, and a hand grasp inclosing the handle portions adapted to force them toward each other.

In testimony whereof I affix my signature this 2nd day of November, 1916.

WILLIAM I. SHERWOOD.
